[57] CLAIM

The ornamental design for a font cartridge for computer output printers, as shown and described.

DESCRIPTION

FIG. 1 is a top plan view of a front cartridge for computer output printers showing our new design;
FIG. 2 is a front elevational view thereof;
FIG. 3 is a rear elevational view thereof;
FIG. 4 is a bottom plan view thereof;
FIG. 5 is a left side elevational view thereof, the right side being a mirror image thereof; and
FIG. 6 is a front, top and right side perspective view thereof.

FIG. 1

FIG. 2

FIG. 3

FIG. 4

FIG. 5

FIG. 6
